UNITED STATES PATENT OFFICE.

GEORGE E. CONRAD, OF STILLWATER, MINNESOTA.

FUSE.

1,367,179.

Specification of Letters Patent.

Patented Feb. 1, 1921.

Application filed July 17, 1919. Serial No. 311,553.

To all whom it may concern:

Be it known that I, GEORGE E. CONRAD, a citizen of the United States, and a resident of Stillwater, in the county of Washington and State of Minnesota, have invented certain new and useful Improvements in Fuses, of which the following is a specification.

My present invention relates generally to fuses and has for its object the provision of 10 an improved construction which will permit of a renewal thereof, or, in other words, the application of a refill, without the necessity of taking the body of the fuse apart, by simply loosening a pair of retaining screws.

15 A further object is the provision of a fuse having means by which the filler, of soft metal construction, may be normally protected and readily exposed to view, as well as one, the condition of which may be 20 instantly determined upon inspection, without the necessity of test.

With these general objects, my invention resides in the features of construction, arrangement, and operation, to be now described with respect to accompanying drawing forming a part of this specification and wherein:

Figure 1 is a vertical longitudinal section through my fuse in its practical application.

30 Fig. 2 is a front elevation thereof.

Fig. 3 is a cross section on line 3—3 of Fig. 2.

Fig. 4 is a front elevation of a slightly different form.

35 Figs. 5 and 6 are respectively a longitudinal section on line 5—5 and a cross section on line 6—6, of Fig. 4.

Referring now to these figures, my improved fuse includes an inner cylindrical shell 10, formed of suitable insulating material with openings axially through its opposite ends for the reception of axial posts 11, projecting inwardly from end caps 13, the latter of which have annular flanges 45 into which the ends of the shell 10 project and are secured by retaining screws 14.

These end caps, which are closed at their outer ends, may be either plain as seen in Figs. 4, 5 and 6, to coöperate with curved 50 retaining clips 15 for the fuse, or may have externally projecting axially extending blades 16 whose inner portions 12 are car-

ried by the caps as seen in Figs. 1 to 3, for use in connection with flat retaining clips 17.

One side portion of the inner shell 16 55 is cut away to provide a longitudinally slotted opening 18, through which the inner portions of the spaced axial posts 11 are exposed. The inner portions of these posts are cut away to present flat seats into which 60 clamping screws 19 are threaded for the purpose of holding upon the flat seats, the opposite ends of the soft metal, or their fuse connection 20, or what is commonly known as the fuse filler. 65

In accordance with my invention, the fuse filler 20 is preferably in the form of a flat strip having a lengthwise slot 21 at one end and a transverse slot 22 adjacent to the opposite end, so that by simply loosening the clamping screws 19, a used filler may be readily removed and a new filler substituted, by first slipping the latter at its longitudinally slotted end in connection with one of the clamping screws and rocking 75 the same to engage its transversely slotted opposite end with the other clamping screw. Then by tightening the screws the renewal operation is complete.

Between the two end caps 13 and around 80 the intermediate portion of the inner shell 10 is an outer rotatable shell 23, one side of which is cut away to provide a longitudinal slotted opening 24, which may be shifted into and out of register with the 85 similar opening 18 of the inner shell 10. Thus, when these openings are registered it is obvious that the filler 20 will be wholly exposed for inspection and to permit of its removal in case removal is found necessary 90 and it is further obvious that in view of this full inspection of the filler, the condition of the same may be readily ascertained so as to entirely avoid the necessity of test to determine whether or not, it is in working condition, as is necessary in most instances with the fuses now in common use. 95

I claim:

A device of the character described including an inner cylindrical shell having 100 end walls provided with central openings, end caps telescoping the ends of said shell and having end walls abutting the end walls of the shell, an outer shell encircling the

inner shell and confined in rotatable relation thereon between the end caps, and terminal posts integral with the end walls of said caps and projecting axially therefrom and inwardly through the end wall openings of the inner shell, said posts having their inner ends spaced apart and provided with flat fuse seats and fuse clamping screws, and

each of said shells having a single opening in its wall extending from one fuse seat to the other, said end caps having outer diametrical grooves, and projecting blades having inner transverse ribs secured in the grooves of the end caps as described.

GEORGE E. CONRAD.
